HYDROMETER

Edward B. Westlake, Jr., Upper Darby, Pa.

Application December 28, 1942, Serial No. 470,421

3 Claims. (Cl. 73—33)

This invention relates to a hydrometer used in measuring specific gravities of liquid such as the freezing point of anti-freeze solution and more particularly to a hydrometer having the stem of the float adapted to project above the hydrometer when in position to be read, thereby eliminating the difficulty encountered by deposits within the glass tube housing the hydrometer bulb in conventional hydrometers now used in various industries.

An object of this invention is to provide a hydrometer wherein the hydrometer bulb projects into the open where it may be easily read.

Another object of this invention is to provide a hydrometer that may be filled at intervals, thereby permitting its use in radiators only partially filled.

Another object of this invention is to provide a hydrometer that may be easily read, wherein the parts are cushioned so as to reduce chances of breakage, a hydrometer that is easily manufactured and at the same time one that is efficient and dependable.

Another object of this invention is to provide a hydrometer provided with a valve system which permits the pumping of the fluid to be tested into the hydrometer and released therefrom when the reading has been taken.

Other objects and advantages reside in the construction of parts, the combination thereof and the mode of operation, as will become more apparent from the following description.

Referring to the drawing,

Figure 1 is a side elevational view of the preferred embodiment of the hydrometer.

Figure 2 is a cross sectional view taken on a plane normal to the axis of rotation of the valve core.

Figure 3 is a fragmentary, cross sectional view of the valve member adjusted through an angle of 90° from the position shown in Figure 2.

Figure 4 is a fragmentary, cross sectional view of the valve member taken substantially on the line 4—4 of Figure 2.

In the drawing, the reference character 10 indicates the main body portion which is provided with a fluid chamber or compartment 12, having enclosed therein a hydrometer float bulb 14 for measuring the specific gravity of the fluid. This float bulb 14 is provided with a graduated stem 16 projecting through a suitable aperture 18 in the top of the main body portion 10. Suitable means have been provided for pumping or sucking and forcing the liquid to be tested into

the compartment 12. The valve and pumping means will now be described.

The device for supplying liquid to the compartment 12 includes a valve member 20 having a hollow cylindrical portion 22 that is provided with an intake passage 24 connected to a suitable hose 26 adapted to project into the liquid to be tested. The cylindrical portion 22 is provided with an outlet passage 28 extending through

10 a cylindrical stem portion 30 projecting into a downwardly directed flange portion 32 integral with the main body portion 10. The main body portion 10 is preferably made from rubber or possibly any other suitable molding material.

15 The valve member may be made from metal, molding material or any other material that may be cast or formed. The cylindrical portion 22 is provided with a core member 40 rotatably mounted in the valve member and provided with

20 a pair of transversely disposed passages 42 and 44. The passage 42 is provided with a pair of spherical segmental members 46 and 48 that function as check valves, permitting the fluid to pass upwardly through the passage 42, but preventing

25 its return.

A rubber suction bulb 50, connected to a suitable tubular extension 52, having a passage communicating with the passage 44, as shown in Figure 1, is used to draw liquid from the source of supply past the lower check valve 46 into the bulb 50. After the bulb 50 has been partially filled with the liquid, it is pressed, so as to force the liquid past the upper check valve 48, as viewed

30 in Figure 2, to fill the compartment 12. The operation may be repeated until sufficient liquid is supplied to compartment 12 to cause some of

35 the liquid to enter into the opening 18 and possibly flow over the top. As the compartment 12 is filled with liquid to be tested, the hydrometer

40 float bulb 14 will rise until the displacement of liquid by the float bulb is equal to its weight.

In order to catch the overflow, the main body portion 10 has been provided with a dish-shaped annular flange 60, forming a cup that catches

45 the overflowing liquid, so as to prevent spilling. When the compartment 12 has been filled and the float bulb 14 has caused the stem 16 to project outwardly through the opening 18, the reading is taken from the graduated scale on the

50 stem 16, where the stem emerges from the opening 18. A suitable scale 62 may be placed on the periphery of the flange portion 32 for interpreting the reading taken from the hydrometer, as will be described more fully later.

55 After the reading has been obtained, the com-

partment 12 and the cup, formed by the annular flange 60, may be emptied by rotating the handle 64 through 90°, so as to rotate the core member 40 through 90°, to cause the passage 44 to register with the intake and outlet openings of the cylindrical portion 22. The core member 40 should be rotated in a counterclockwise direction, as viewed in Figure 1, to cause the enlarged end 70 of the passage 44 to register with the passage 28 and a drain passage 72, draining the cup formed by the dish-shaped annular flange 60. This permits all of the liquid to return to the source of supply, without spilling any and without any waste. Any suitable means may be used to limit the rotation of the core member 40 in either direction. For the purpose of illustration, stop members 65 are used to limit the movement of the handle 64 and thereby limit the movement of the core member 40.

Due to the fact that specific gravity of liquids is influenced by temperature, a thermometer 80, mounted in the side wall of the compartment 12 and having a bulb 82 contacting the liquid in the compartment 12, is used to measure the temperature of the liquid under test. A longitudinal slot extending through the side wall of the compartment has embedded therein the thermometer 80, so that one side of the thermometer is visible from the outside of the wall, as seen in Figure 1, and the other side including a portion of the bulb is exposed to the contents of the compartment. After the temperature has been taken and the reading obtained from the hydrometer, it is merely necessary to refer to the scale or table 62 to ascertain the desired characteristic of the liquid. If, for example, the hydrometer is to be used in testing anti-freeze solutions, a suitable table is provided for a particular solution. It may be found that for a given temperature, say 100° F., and a particular reading on the hydrometer, the table will indicate that the anti-freeze will protect the radiator for any temperature higher than 20° below zero, or whatever the table may indicate.

In the check valve arrangement shown, spherical segmental valve members 46 and 48 are seated upon suitable valve seats and held in position by a pair of transverse pins 100. Instead of using spherical segmental valve members, any other suitable check valves could be used. Likewise, they may be held in position in any suitable manner. These have been merely shown for the purpose of illustration.

As described above, the temperature has been read from the thermometer located in the side wall of the compartment 12. Instead of reading the temperature of the liquid to be tested upon this thermometer, the temperature of the liquid may be read by means of the thermometer 98 mounted within the bulb 14. Due to the fact that the stem of the hydrometer bulb 14 is made of glass, the thermometer mounted within the stem is visible as though it were mounted on the outside of the stem of the hydrometer bulb. When a thermometer is mounted within the tube or stem, the stem is provided with two scales, one for reading the specific gravity of the liquid and the other for reading the temperature. This is a matter of choice as far as the invention is concerned.

From the foregoing, it may be clearly seen that no difficulty should be encountered in taking the hydrometer reading due to dirt or a sediment being deposited upon the parts from which the reading is taken, in that the stem 16 is not en-

closed in a glass tube, but projects into the opening, so that it may be clearly seen without vision being obscured by a dirty glass tube surrounding the stem. If, perchance, the stem should become soiled, the surface can be readily wiped clean in much the same manner as the stem of a thermometer.

Although the preferred modification of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A hydrometer including a main body having a compartment near the top thereof, said compartment having an opening in the top, a hydrometer bulb mounted in the compartment, said bulb having a graduated stem projecting through the opening in the top of the compartment, means for filling the compartment with liquid to be tested, said means including a valve having an outlet passage communicating with the compartment, said valve having a core member provided with intersecting transversely disposed passages one of which passages is open, a pair of check valves mounted in the other of said passages, there being one check valve to either side of the intersecting passage, and suction means communicating with the open passage when the passage having the check valves registers with the outlet opening of the valve.

2. A hydrometer having a downwardly projecting hose adapted to be inserted into the intake opening of a motor vehicle radiator, said hydrometer including a compartment provided with an exposed opening at the top, means for filling the compartment with liquid to be tested, said means including a hollow compressible bulb and a pair of check valves, one of the check valves being located between the compressible bulb and the lower end of the hose and the other check valve being located between the compressible bulb and the compartment, one of said check valves allowing liquid to flow into the bulb and the other allowing liquid to flow out of the bulb into said compartment, and a hydrometer bulb provided with a graduated stem, the hydrometer bulb being mounted within the compartment and the stem projecting through the opening in the top of the compartment so that the stem projects upwardly from the top of the compartment so as to take the reading of the graduated stem at the point where it emerges from the compartment.

3. A hydrometer having a downwardly projecting hose adapted to be inserted into the intake opening of a motor vehicle radiator, said hydrometer including a main body having a compartment near the top thereof, means for drawing liquid into the compartment, said means including a hollow compressible bulb and a pair of check valves, one of the check valves being located between the bulb and the lower end of the hose and the other check valve being located between the bulb and the compartment, said compartment having an upwardly directed opening, a cup portion surrounding the main body, said main body having a downwardly directed tubular portion provided with a pair of substantially parallel passages, said passages terminating at their lower ends in close proximity to each other, one of said

passages communicating with the compartment and the other passage communicating with the cup portion surrounding the body to catch the overflow from the compartment, a bulb having a graduated stem mounted in the compartment, said stem projecting upwardly through the upwardly directed opening, a valve interconnected to the lower end of the tubular portion, said valve having a pair of passages communicating with the passages in the tubular portion, a core mem- 10

ber mounted in the valve, said core member being provided with a pair of intersecting transversely disposed passages, the opening to one of the passages in the core being greater than the opening to the other passage in the core, so that when the passage provided with the larger opening is moved into registry with said pair of parallel passages drainage from the compartment and the cup portion is provided.

EDWARD B. WESTLAKE, JR.
